CLAIM

The ornamental design for a baseball, as shown and described.

DESCRIPTION

FIG. 1 is a front perspective view of a baseball showing my new design;

FIG. 2 is a rear perspective view thereof;

FIG. 3 is a top perspective view thereof;

FIG. 4 is a bottom perspective view thereof;

FIG. 5 is a left side perspective view thereof; and,

FIG. 6 is a right side perspective view thereof.

The Earth Day logo which appears in FIG. 2 and the Fotoball logo which appears in FIG. 4 do not form a part of the design and both logos are hereby specifically disclaimed.

The file of this patent contains at least one photograph executed in color. Copies of this patent with color photographs will be provided by the Patent and Trademark Office upon request and payment of the necessary fee.
